DESIGN.

A. H. SMITH.
SIDE DRIER FRAME.

No. 24,594.

Patented Aug. 20, 1895.

UNITED STATES PATENT OFFICE.

ALFRED HENRY SMITH, OF WILMINGTON, DELAWARE.

DESIGN FOR A SIDE DRIER-FRAME.

SPECIFICATION forming part of Design No. 24,594, dated August 20, 1895.

Application filed January 17, 1895. Serial No. 535,275. Term of patent 7 years.

To all whom it may concern:

Be it known that I, ALFRED HENRY SMITH, a citizen of the United States, residing at Wilmington, in the county of Newcastle and 5 State of Delaware, have invented and produced a new and original Design for a Side Drier-Frame for Paper-Making Machines, of which the following is a specification.

Reference is to be had to the accompanying drawings, in which—

Figure 1 is a side elevation of a side drier-frame for paper-making machines embodying my design, and Fig. 2 is a section on line 2 2 of Fig. 1.

5 The leading feature of the design consists in a lower section A, from which rise the pillars B, having side extensions C at their upper ends.

The lower section A consists of a series of approximately T-shaped parts A', arranged 20 one alongside the other, and supporting at one end of the horizontal member one of the pillars B.

A minor feature of my design is the arched top bar D resting on the ends of the side extensions C.

I claim—

The design for a side drier frame for paper making machines, as herein shown and described.

ALFRED HENRY SMITH.
